UNITED STATES PATENT OFFICE.

FRANK A. LUCAS, OF PADUCAH, KENTUCKY.

NON-REFILLABLE BOTTLE.

SPECIFICATION forming part of Letters Patent No. 710,875, dated October 7, 1902.

Application filed June 16, 1902. Serial No. 111,901. (No model.)

To all whom it may concern:

Be it known that I, FRANK A. LUCAS, a citizen of the United States, residing at Paducah, in the county of McCracken and State of Kentucky, have invented new and useful Improvements in Non - Refillable Bottles, of which the following is a specification.

My invention relates to non-refillable bottles; and the object of the same is to construct a device of this character which cannot be refilled when once emptied.

The simple and novel construction employed by me in carrying out my invention is fully described in this specification and claimed, and illustrated in the accompanying drawings, forming a part thereof; in which—

Figure 1 is a longitudinal section of my bottle. Fig. 2 is a detail of the plug. Fig. 3 is a horizontal section of the neck with plug removed, taken on the line 3 3, Fig. 1.

Like numerals of reference designate like parts in the different views of the drawings.

The numeral 1 designates a bottle having a body 2 and a hollow neck 3, formed integral therewith. The neck is traversed by a bore 4, reduced at 5 to form a valve-seat, which is reamed out at 5^a to accommodate a ball 6, designed to prevent the entrance of liquid into the bottle. The bore 4 is traversed throughout a portion of its length by a coarse thread 7, which serves to engage and retain a screw-plug 8, fitted in the neck. The plug 8 is formed in two parts—to wit, a hollow threaded body 9 and a perforated head 10—which bear a series of beveled ratchet-teeth 11, which mesh with a like series 12 of teeth formed in the body 9. The teeth 11 and 12 are so beveled that they will hold positively when the head is turned, so that the plug 8 will be screwed down into the neck, but will ride over each other and permit the head 10 to turn independently of the body 9 when the head is turned counter-clockwise in the direction to unscrew the plug. This renders it possible to screw the plug 8 into the neck 3, but impossible to screw it out. The head

10 bears a flange 13, which engages a groove 14 and holds it against removal from the neck, but permits it to turn freely. Grooves 15, traversing the neck 3 longitudinally, admit air to the bottle.

In assembling my bottle the ball 6 is dropped into its seat 5 and the plug 8 inserted and screwed into the neck by means of a wrench inserted in the perforation 10^a in the head 10. After the plug has once been screwed down it will be impossible to remove it.

I do not wish to be limited as to details of construction, as these may be modified in many particulars without departing from the spirit of my invention.

Having described my invention, what I claim as new, and desire to secure by Letters Patent, is—

1. In a bottle, the combination with a neck 65 having a threaded bore therein reduced to form a valve-seat, a valve mounted in said seat and arranged to prevent the entrance of liquid into the bottle, and a plug fitted in said bore and comprising a threaded body 70 bearing ratchet-teeth, and a head bearing ratchet-teeth engaging said ratchet-teeth formed on said body, substantially as described.

2. In a bottle, the combination with a neck 75 having a threaded bore, a valve-seat in said bore, a valve mounted in said seat, an apertured plug mounted in said bore and comprising a threaded body and a head constructed to positively engage said body and 80 turn in unison therewith in screwing said plug into the neck but to turn independently of said body when it is attempted to unscrew the plug to remove it from the neck, substantially as described.

In testimony whereof I have hereunto set my hand in presence of two subscribing witnesses.

FRANK A. LUCAS.
